FEATHERING PROPELLER

Louis Sveinssen, Shamokin, Pa.

Application May 29, 1934, Serial No. 728,155

6 Claims. (Cl. 259—133)

This invention relates to feathering propellers. It is an important object of the invention to provide a novel construction of propeller in which the blades thereof may be manually rotated on their axis to vary the setting of the blades, from a remote point, during operation of the propeller.

It is a further object of the invention to provide a propeller of the character set forth, wherein in automatic means is provided, operable independently of the manual means, for adjusting the propeller blades.

It is a still further object of the invention to provide novel means, manually operable for tilting the propeller as a unit, as well as the provision of novel propeller blade construction for creating a simultaneous reverse whirling flow of fluid during rotation of the propeller.

Additional objects, advantages and features of invention will be apparent from the following description, considered in conjunction with the accompanying drawings, wherein

Figure 1 is a sectional view of a propeller unit constructed in accordance with my invention.

Figure 2 is a cross section on the line 2—2 of Figure 1.

Figure 3 is a cross section on the line 3—3 of Figure 1.

Figure 4 is a cross section on the line 4—4 of Figure 1.

Figure 5 is a detailed illustration of one of the propeller blades.

Figure 6 is a view illustrating the shape of the blade on sections therethrough, at the points designated by the construction lines.

Figure 7 is a view similar to Figure 1 illustrating a modification.

Figure 8 is a cross section on the line 8—8 of Figure 7.

Figure 9 is a cross section on the line 9—9 of Figure 7.

In many industries there has been created a demand for propellers in which the blades are "feathered" to increase or decrease the draft of liquid or air upon rotation of the propeller, and the present type of propeller was particularly designed for use in connection with a coal and slate separating apparatus, for which I have applied for Letters Patent, by an application filed April 16th, 1934, Ser. No. 720,862, and while the structure here presented is admirably suited for the purposes set forth, I realize that the invention is subject to application in numerous situations, and I therefore do not confine myself to the particular construction set forth, but reserve

as my own, all such modifications as fairly fall within the scope of the appended claims.

In carrying out the invention, as applied to a coal and slate separating apparatus, I have illustrated a wall 10, representing a portion of a tank 11 employed in the apparatus. The wall is provided with a suitable aperture 12, around which there is bolted, as at 13, a housing 14. The housing 14, in the present instance, is shown as a cylindrical drum, the open end of which 10 registers with the aperture 12 of the wall. The opposite end of the housing 14 is defined by having the walls thereof disposed inwardly to form a cone-shaped bearing 15, and within the housing 14 and rockably journaled in the bearing 15, I mount the propeller unit generally indicated by the reference character 16.

The propeller unit 16 has a bearing shell 17 rockably supported within the bearing 15, as indicated at 18, and houses a roller bearing 19 which in turn supports a hub 20 of a propeller head 21.

The propeller head 21 may have any desired shape to support the required number of blades, and is hollow in order to accommodate mechanism for effecting feathering action of the blades, as will be presently described. The head 21 is also preferably formed in two half sections 22—23 bolted together, as indicated at 24. Each section 22—23 is provided with the required number 30 of radial hollow extensions 25 which, when mated together, define a hub 26 through which the axle portion 28 of a propeller blade 29 is journaled. The sections 22—23 are also provided with suitable ball races 30 for anti-frictionally supporting the axle 28, and the inner extremity of the axle 28 is threaded as at 31, and has engaged thereon a nut 32 which bears upon a washer 33 in seated engagement with an annular kerf formed in the sections 22—23. 35 In order to account for end thrusts which may occur in the axle 28, a ball race 34 is provided between the washer 33 and a seat 35 formed in the hub 26. A packing gland 36 and clamping ring 36a may be provided, encircling the extensions 25, which will prevent ingress of grit or other foreign matter in the interior of the propeller unit, as well as prevent escape of lubricant, which is conducted to the several bearings 45 through the oil ducts 37.

The washer 33 has a square or angular hole therethrough and the axle 28 is correspondingly shaped at the point of contact with the washer, so that the blade 29 may be rotated upon rotation 55 of the washer, as will now be described, and ref-

erence is now invited to Figure 2 of the drawings. An arm 37' is integrally formed with the washer 33 extended at right angles thereto and is positioned within a slot 38 formed in an arm 5 39 of an operating head 40.

The present construction of propeller unit embodies three propeller blades 29 and therefore, three sets of extensions 25 are involved, each of which are constructed as above described, and it 10 will be understood that the number of blades involved is a matter of choice. Obviously, from the construction described, endwise movement of the head 40 will impart a partial rotation of the blades 29, and such endwise movement of the head 15 is effected through the mechanism now to be described.

As clearly shown in Figure 1 of the drawings, the head 40 includes a shaft 41 journalled in the hub 29, projecting a substantial distance outwardly thereof in the form of a guide, pintle 42. A shell 43 is bolted to the hub 29, as at 44, and within the shell there are pivotally mounted, as at 45, weight members 46, each of which include a bill portion 46a engaged within respective 20 pockets 47 formed in the shaft 41. It should be understood that the shell 43 and hub 29 will rotate as a unit, and due to centrifugal action of the weights 46, endwise movement of the shaft 41 will occur, imparting partial rotation to the 25 propeller blades, by virtue of its connection with the arms 39.

As shown, a thrust bearing 48 is positioned between the shell 43 and the roller bearing 49, and if desired, the bill members 46 may have a roller 30 50, for the purpose of reducing friction and wear.

The arms 39 are shown as separate members suitably bolted as at 51, to flattened portions formed on the shaft 41, and in order to prevent rotation of the shaft independently of the propeller unit 21, the sections 22-23 are provided 40 with channels 52 within which the extremities of the arms are engaged.

The shell 43 is provided with inwardly extended flanges 53, acting as guide means for the weight 45 members 46, and these flanges 53 stop short of the central medial portion of the shell where they merge with a pair of arms 54 extended in a plane parallel with the shaft 41. A thrust bearing 55 is 50 slidably mounted upon the arms 54, and the shell 55 42 is cut away as at 56 to permit the bearing 55 to slide thereto a short distance, as would be required during manual adjustment of the blades. The pintle 42 is journalled in the bearing 55 as indicated at 57, and a coiled spring 58 is seated 55 between the end of the shaft 41 and the thrust bearing 55.

A drive shaft 59 is provided and includes a universal joint 60 connected with the arms 54 and it will be clearly seen that rotation of the 60 drive shaft 59 will impart rotary motion to the propeller head 21 by virtue of its connection with the shell 43, and that automatic adjustment of the blades 29 is brought about through movement of the weights 46. However, it is essential that 65 manual setting of the blades be permitted, and I therefore provide a collar 61 in abutting relation with the thrust bearing 55, and preferably I interpose a ball-race 62 between the collar and bearing. The collar 61 includes a ring gear 63 70 and a screw threaded body portion 64. A supporting ring 65 having been internally formed with screw threads is in engagement with the threads of the body 64, and upon the exterior of the ring 65, a bearing 66 is arranged. The bearing 75 66 revolutely journals a shaft 67 which has

keyed thereto a gear 68 in mesh with the ring gear 63, the other end of the shaft projecting exteriorly of the tank 11 and has fixed thereto a hand wheel 69. Therefore, it will be understood that upon rotation of the shaft 67 the collar 61 will be correspondingly rotated, and inasmuch as the supporting ring is retained by guide-ways 70 against rotation and endwise movements the collar 61 will be advanced or retracted according to the direction of rotation of the shaft 67. Assuming that the shaft 67 is rotated in a right hand direction, as seen in Figure 1, the collar 61 will be advanced in the direction of the propeller head 21, and such movement it will be seen will advance the shaft 41, under compression of 10 the spring 58. Endwise movement of the shaft 41 will impart a rotary movement of the propeller blades 29 by reason of the connection between the head 40 and the arms 37. The opposite rotation of the shaft 67 will of course effect a reverse 20 movement of the parts, with a corresponding reverse setting of the blades 29.

In order to secure a tilting action of the propeller as a unit, the supporting ring 65 has a pair of oppositely extended lugs 71 disposed in respective trackways 72 previously referred to. The trackways 72 are secured to the sides of the housing 14, and are arcuately disposed with respect to the pivot points 18, so that upon movement of the hand lever 72 which is pivotally secured to 30 the ring 65, as at 73, the ring will be caused to travel within the trackways 72, the propeller unit 16 being swung upwardly or downwardly from a horizontal plane on the pivot points 18, which swinging movement is permitted by virtue of the 35 universal joint 60 between the drive shaft 59 and the arms 54 of the propeller unit.

The lever 72 extends exteriorly of the tank 11, as shown and intermediate its length there is provided a fulcrum pin 74 disposed within a slot 40 75 formed in the lever.

It is desirable that a water-tight joint be provided between the bearing sleeve 17 and the bearing 15, and in the present instance I have illustrated a flexible boot 17a constructed to lie flush 45 upon the inner wall of the bearing 15 and held in place thereagainst by an annular flange 15a. The flange 15a is suitably apertured, as is the boot, and bolts 18a inserted therethrough and in tapped apertures formed in the bearing will effectively secure the boot to the bearing in a water-tight manner. The other end of the boot 17a is recurved as at 19a to snugly circumscribe the sleeve 17 and is secured thereto by a clamp strap 20a. From the construction described, it will be 55 apparent that water will be effectively prevented from entering through the housing 14 and yet permit free rocking movements to position the propeller at desired angular settings.

As was set forth in my co-pending application 60 Ser. No. 720,862 the propeller blades are constructed to provide a simultaneous whirling opposite flow of fluid, and in Figures 5 and 6 a detailed showing of one of the propeller blades is shown. The blade 29 it will be seen from a consideration 65 of Figure 6 has its leading edge 76 nearest the hub of the propeller, formed at an angle opposite to that of the edge 77 adjacent the tip of the propeller, and portions of the blade intermediate the hub and tip will be correspondingly formed, as 70 indicated by the various cross sections indicated at A, B, C, D, E, F, and G. Thus, a propeller constructed in accordance with the above blade during rotation, it will be apparent that the leading edge 76 will tend to draw fluid toward the 75

propeller at a point closely adjacent the hub and a short distance outwardly thereof while the leading edge 11 will force the fluid outwardly away from the propeller, thereby creating a "push" and "pull" of the fluid, simultaneously.

5 In order to provide lubrication to the bearings 19 and 48, the shaft 41 and the pintle 42 have a bore 94a extending longitudinally therethrough from one end to the other, one end being closed 10 by a screw plug 57a which may be readily removed for the purpose of replenishing the supply of lubricant. Lateral ducts 97a are formed in the shaft 42 opening upon ports opposite respective bearings 19 and 48.

15 In Figures 7 to 9 I have illustrated a form of propeller in which the automatic features of adjusting the propeller blades is dispensed with, the adjustment being provided for by means which are entirely manual. In this form, the propeller 20 head, blade mounting, and blade moving means 25 are identical with the form first described and therefore the same reference numerals have been employed to designate corresponding parts.

20 The tank 11a is provided with an opening 78 25 of a size to freely receive a cylindrical shell 79 therethrough and which is in screw threaded engagement with a plate 80 aligned with the aperture 78 and securely bolted, as at 81 to the tank 11a. The shell 79 projects exteriorly of the tank 30 and has fixed thereto a hand wheel 82, whereby the shell may be manually rotated. The opposite end of the shell is also provided with screw threads 83 upon which a packing gland collar 84 is engaged. As may be clearly seen in Figure 35 7, the collar 84 has seating engagement with a shoulder 85 of the propeller head 21, and therefore it will be impossible for foreign matter, such as grit, gaining access into the interior of the shell.

40 The hub 20' of the propeller is revolvably mounted within a roller bearing assembly 86 secured within the shell 79, and a thrust bearing assembly 87 is also mounted within the shell, interposed between the assembly 86 and the shoulder 85 of the propeller head. A similar thrust bearing assembly 88 is mounted within the shell positioned between the bearing assembly 86 and a retaining plate 89, bolted as at 90, to the end 45 of the hub 20.

50 From the foregoing, it will be apparent that inasmuch as the bearing assemblies 86, 87 and 88 are securely held within the shell against longitudinal movements, the propeller head 21 will also be held against such movement but free rotary movement of the head will be permitted. In order to impart such rotary movement to the propeller 21, the interior of the hub 20' is provided with a plurality of longitudinally extending splines 91 adapted to register with recesses 92 55 formed in the periphery of a drive shaft 93. The recesses 92 extend longitudinally of the shaft, and from this construction it will be clearly seen that with rotation of the shaft 93, the hub 20' and associated propeller will be rotated, and that while undergoing such movements the shell 79 may have longitudinal movement imparted thereto by manipulation of the hand wheel 82, by virtue of the spline and recess connection between the drive shaft and hub.

60 The drive shaft 93 has a longitudinal bore 94 extending from the extremity enclosed within the propeller head to a point exteriorly of the tank 11a where it is joined by a lateral duct 95, closed by a screw plug 96. At points opposite the bearing assemblies 86, 87 and 88, lateral ducts 97 are

formed in registry with ports 98 formed in the hub 20'. By the duct and port arrangement set forth, it will be understood that lubricant may be fed to the various bearings of the assemblies.

65 In order to effectively maintain the drive shaft 93 against endwise or longitudinal movements, the shaft is provided with a ball member 99, anti-frictionally supported as at 100 in a thrust block 101. The block 101 may be suitably mounted upon a stationary upright 102, and it will be apparent that the block 101 in addition to preventing endwise movements, also adds stability to the drive shaft.

70 Any suitable drive means may be associated with the shaft 93, but in the present instance, I have shown a bevel gear 103 fixed to the shaft 93, in mesh with a similar gear 104 keyed to a power shaft 105.

75 When it is desired to vary the setting of the blades 29, the hand wheel is rotated, causing a rotation of the shell 79. Due to the screw threaded engagement between the shell and plate 80, the shell will be caused to move endwise of the drive shaft 93 and inasmuch as the arms 37 of the washers 33 are engaged within the slots 38 of the head 40, the propellers 29 will be given a partial rotary movement, in one direction, or the other, depending upon the direction of rotation of the hand wheel 82.

80 I claim:

1. A feathering propeller comprising a housing, a bearing mounting, a bearing rockably supported therein, a propeller head having a hub revolvably mounted in the bearing, oscillatable blades carried by the head, each blade having an arm, a shaft positioned within the hub, one end thereof being connected with respective arms, slots formed in the opposite end of the shaft, a casing fixed to the hub and rotatable therewith, the casing having arms extended therefrom, a drive shaft connected with the arms to impart rotary movement to the casing and hub, opposed trackways carried by the casing, a collar positioned around the arms and having lugs positioned within the trackways, a lever pivoted on the housing and connected with the collar to move the same through the trackways; the collar having internal screw threads, a sleeve in screw threaded engagement with the threads of the collar, a thrust bearing slidably supported by the last named arms and in abutting relation with the sleeve, a helical spring interposed between the first named shaft and the thrust bearing, means for rotating the sleeve and centrifugally acting weight members pivoted within the casing, each weight member having a bill portion positioned within respective slots of the shaft.

2. A feathering propeller comprising a longitudinally movable casing having bearing means therein, a hollow propeller head associated with the casing in abutting relation thereto and having a hollow hub journaled in the bearing, propeller blades oscillatably mounted in the head, each blade having an arm, splines upon the hollow hub portion, a revolvable drive shaft extended through the casing and having a head member disposed with the hollow propeller head, said head having means for connection with the arms of the propeller blades, longitudinally extending slots formed on the periphery of the drive shaft and receiving the splines of the hub, means for rotating the shaft, and means for imparting longitudinal movement of the casing and the head with respect to the rotary shaft.

3. A feathering propeller comprising a longi-

tudinally movable casing having bearing means at one end thereof, a hollow propeller head associated with the casing in abutting relation thereto and having a hollow hub revolvably journaled in the bearing, blades oscillatably mounted in the head, each blade having an arm, splines and slots upon the interior of the hub, a drive shaft extended through the casing, one end having a head member positioned within the hollow propeller head, said head having apertures for reception of respective arms of the propeller blades, longitudinally extending splines and slots formed on the periphery of the drive shaft for inter-engagement with splines and slots of the hub, a thrust and supporting bearing for the other end of the shaft, a bevel gear fixed to the shaft, a bevel gear in mesh therewith and having a driven shaft, a stationary bearing for the casing, said bearing having internal screw threads, external screw threads on the casing cooperative therewith, and a hand wheel on the casing for rotating the casing.

4. A feathering propeller comprising a bearing, a propeller head having a hub revolvably mounted in the bearing, oscillatable blades carried by the head, each blade having an angularly extended arm, a revolvable shaft extended through the bearing and into said head for operative connection with respective arms of the blades, means

for rotating the shaft, and rotary means associated with the head to oscillate the arms, whereby to vary the setting of the blades.

5. A feathering propeller comprising a housing, a rockable bearing therein, a propeller head having a hub revolvably supported in the bearing, oscillatable blades carried by the head, each blade having an arm, a shaft positioned within the head and extending through the hub, respective arms being connected to the shaft, means for rotating the shaft, means for imparting longitudinal movements to the shaft upon rotary movement thereof, and means for rocking said bearing.

6. A feathering propeller comprising a housing, a rockable bearing therein, a propeller head having a hub revolvably mounted in the bearing, oscillatable blades carried by the head, each blade having an arm, a shaft positioned within the hub, one end thereof being connected with respective arms, automatic means at the opposite end of the shaft for imparting longitudinal movement to the shaft upon rotation thereof, a drive shaft having universal connection with the hub of the propeller head, means associated with the first named shaft for manually imparting longitudinal movement thereto, and means for tilting the rockable bearing.

LOUIS SVEINSSON.
